US00D809934S

(12) **United States Design Patent** (10) Patent No.: **US D809,934 S**
(45) Date of Patent: **** Feb. 13, 2018**

(54) **TRAY**

(71) Applicants: **FiveStar Gourmet Foods, Inc.**,
Ontario, CA (US); **Direct Pack, Inc.**,
Azusa, CA (US)

(72) Inventors: **Tal Shoshan**, Alta Loma, CA (US);
Kevind-Dirk Pesirla Closas, Ontario,
CA (US); **Cesar E. Ramirez**, Montclair,
CA (US)

(73) Assignees: **FiveStar Gourmet Foods, Inc.**, Ontario
(CA); **Direct Pack, Inc.**, Azusa, CA
(US)

(**) Term: **15 Years**

(21) Appl. No.: **29/613,998**

(22) Filed: **Aug. 15, 2017**

(51) LOC (11) Cl. **09-03**

(52) U.S. Cl.
